UNITED STATES PATENT OFFICE.

GORDON M. TYRRELL, OF NEW HAVEN, CONNECTICUT.

BUCKLE.

SPECIFICATION forming part of Letters Patent No. 404,323, dated May 28, 1889.

Application filed September 8, 1888. Serial No. 284,860. (No model.)

To all whom it may concern:

Be it known that I, GORDON M. TYRRELL, a citizen of the United States, residing at New Haven, in the county of New Haven and State 5 of Connecticut, have invented certain new and useful Improvements in Buckles; and I do hereby declare the following to be a full, clear, and exact description of the invention, such as will enable others skilled in the art 10 to which it appertains to make and use the same.

My invention relates to an improved buckle for suspenders and similar articles that will firmly clasp the strap.

15 The invention consists in the various features of improvement more fully pointed out in the claims, reference being had to the accompanying drawings, in which—

Figure 1 is a front view of my improved 20 buckle. Fig. 2 is a front view of the buckle-frame with the slide removed. Fig. 3 is a longitudinal section on line $\alpha\alpha$, Fig. 1. Fig. 4 represents the slide, and Fig. 5 is a perspective view showing the inturned edge provided with teeth.

A is the frame of the buckle, having a hook, B, upon its lower end and the top turned inward and teeth formed thereon to grasp the strap.

25 On each side of the buckle-frame A are spring-arms $a a$, formed by cutting transverse and longitudinal slots in the frame.

C is the slide, which partially encircles the buckle-frame, and having its bent ends $c c$

resting upon the spring-arms $a a$ on the face 35 of the buckle-frame. To prevent the slide C from slipping off of the end of the buckle-frame, the sides of the frame where the spring-arms are formed are beveled, so that the frame is wider at the base than at the top.

40 The operation is as follows: The strap D is passed between the frame A and slide C, and the slide pushed into position over the spring-arms $a a$, which presses them inward and causes them to act as a cam and hold the 45 strap tightly in place. If the slide should not be placed in its correct position, a slight pull upon the hook D will cause it to immediately assume its place.

Having fully described my invention, what 50 I claim is—

1. The combination of a frame, A, having an inwardly-turned upper edge and provided with spring-arms $a a$, formed integral with its side, with a movable slide, C, to operate said 55 spring-arms, substantially as set forth.

2. The combination of a frame, A, having an inwardly-turned upper edge, and beveled sides having spring-arms $a a$, formed integral therewith, with a movable slide, C, to operate 60 said spring-arms, substantially as set forth.

In testimony whereof I affix my signature in presence of two witnesses.

GORDON M. TYRRELL.
